UNITED STATES PATENT OFFICE.

EMILIO RODRIGUEZ ETCHETO, OF BUENOS AIRES, ARGENTINA.

PROPAGANDA APPARATUS APPLICABLE TO ELECTRICAL FANS OR MOTORS.

Application filed November 9, 1922, Serial No. 599,946. Renewed February 18, 1925.

To all whom it may concern:

Be it known that I, EMILIO RODRIGUEZ ETCHETO, a citizen of the Argentine Republic, and a resident of Buenos Aires, Argentine Republic, have invented a new and improved Propaganda Apparatus Applicable to Electrical Fans or Motors, of which the following is a full, clear, and exact description.

10 My invention refers to a propaganda apparatus which can be affixed to any class of electric fan. For the sake of greater clearness the invention is illustrated in various figures, viz;

15 Figure 1 is a view in front elevation of an apparatus without disks, but showing the drum or cover to demonstrate the distribution of the electric bulbs,

20 Figure 2 is a view in side elevation of the device and partly in section to show the construction of drums and parts carried therein,

Figure 3 is a view in front elevation of the translucent disk and the stationary member carried thereby,

25 Figure 3^a is an edge view of translucent disc,

Figure 4 is a view in elevation of the transparent color disc,

Figure 5 is a similar view of the obturator,

30 Figure 6 is a view in side elevation of the device when affixed to a fan, and

Figure 7 is a detail sectional view drawn to a larger scale and showing parts carried by the auxiliary axle,

35 Figure 8 is a view in side elevation of a double apparatus.

The apparatus invented by me consists of a number of transparent disks, one with painted letters constituting the text of the advertisement, another painted in various colors in sectors, a disk of opaque glass, a two-winged obturator disk, some electric bulbs, and a drum or cover enclosing all the disks, the whole apparatus affixed to a common fan motor.

40 First of all the blades (11) are taken off the fan (1), and onto the axle of the motor an auxiliary axle (10) is placed serving as a prolongation of the former shaft (see Figs. 2, 6 and 7).

45 This auxiliary axle (10) is affixed to the axle of the motor by means of a screw (12). The drum (2) is then affixed by means of the screws (3) with which the lid of the casing of the motor is fastened onto the motor. Preferably four electric bulbs (4) are affixed within the

drum, the wires being connected directly or by means of intermittence apparatuses (23) with the wire which supplies the motor with electric current. In front of the bulbs (4) a transparent disk (5) of ground glass or some other suitable material is affixed, the object of this disk being to diffuse the light derived from the bulbs (4). In the centre of the disk (5) is formed a hole of a convenient diameter on the edge of which a grooved ring (13) is applied to serve as supporting seat for a half or entire transparent disk (6) on which the text of the advertisement is written. This disk (6) is exchangeable and is introduced into the apparatus through an opening (22) formed in the circumference of the drum (2).

50 Onto the auxiliary axle (10) is now applied a disk (7). This disk is loose so as to revolve on the axle (10) and, like the others, transparent, and is made from celluloid or some other material and conveniently painted in various sectors or in "iris" fashion with different colours. This disk is provided with a metal bush (14) and with two or more openings, windows or transparencies (20 and 21) on its surface, serving the object of making it possible to read the lettering, and which for this reason must be of the same radius as the letters of the disk (6). The obturator disk (8) consisting of two great blades or wings is now put on; these blades, which must be black, can be made from tin plate, brass or some other convenient material. The obturator, which may be of various shapes, may in parts consist of transparent coloured material so as to obtain a larger number of shades of colour. The obturator (8) is provided with a bush (17) affixed to it by means of screws. This bush (17) has a pressure screw (18) for fastening it onto the auxiliary axle (10). Between the disk (7) and the obturator (8) a ring (16) is affixed, same being made from gutta-percha, rubber, ebonite or some other adequate material so as to produce friction against the disk (7) and thus imparting variable revolutions to same according to the degree of its rubbing against the ring (16) which may be tightened at will by means of the bush (17) of the obturator (8).

55 Finally a disk of clear glass (9) is now put onto the frame or edge of the drum (2), allowing the axle to revolve freely since the disk (9) is provided with a sufficiently large hole in the centre.

Once all this has been done the blades of the fan are affixed at the extremity of the auxiliary axle.

In the drum (2), conveniently distributed, 5 some ventilation holes have been provided.

As shown in Fig. 8 a double apparatus can also be constructed using the two extremities of the motor axle.

In cold weather or in the winter the fan 10 can also be used as a propaganda apparatus by simply taking the blades off.

The working is very simple since when the fan is started, same and the obturator revolve with the identical high number of 15 revolutions, and, in consequence, the obturator by means of the ring (16), which, as already stated above, is made from rubber, gutta-percha or some other material, and the axle itself, also impart high revolutions 20 to the transparent disk painted in various colours, but these revolutions instead of being constant are alternating according to the time of friction with the ring, and in conformity with these alternating revolutions 25 the inscriptions of the disk (6) appear. The bulbs affixed behind all the disks light up the whole so that when the colour disk performs its alternating revolutions in combination with the high and constant revolutions 30 of the obturator, the effect of vari-coloured rings changing every moment is produced, and in these rings the inscriptions appear periodically, the whole producing an aesthetic effect which also catches the eye.

35 Having thus described my invention and the manner of putting it into practice, I declare that what I claim as my invention and exclusive property is:

1. A device of the character described, 40 comprising a stationary translucent member, a source of light at the rear of said member, a stationary transparent member forward of the first member and having characters thereon, a rotatable member forward 45 of the last named member and having slots through which said characters may be observed and also having colored sections, and a rotatable obturator forward of the said rotatable member.

50 2. In combination with an electric motor of the character described, a cylinder housing, means whereby the housing may be secured to the motor and extend axially with the drive shaft of said motor, means for supporting electric lights within the housing upon the inner end thereof, a stationary 55 translucent member carried by the housing and positioned forward of said lights, a member of transparent material carried by the 60 housing and positioned on the forward side of the translucent member and having characters thereon, a member mounted on the shaft of said motor to have variable 65 rotary movement and positioned forward of the character member, the said member be-

ing transparent and having slots through which the characters upon the said member may be observed, and an obturator mounted on the said shaft forward of said member.

3. In combination with an electric motor 70 of the character described, a cylinder housing, means whereby the housing may be secured to the motor and extend axially with the drive shaft of said motor, means for supporting electric lights within the 75 housing upon the inner end thereof, a translucent member carried by the housing and positioned forward of said lights, a stationary member of transparent material carried by the housing and positioned on the forward side of the said translucent member and having characters thereon, a disc loosely mounted on the shaft of said motor and positioned forward of the character member, the disc being transparent and having slots 80 through which the characters upon the said member may be observed and also having sections of different colors, and an obturator fixedly secured to the shaft forward of the 85 said disc, and means for imparting variable 90 rotary movement to the said disc.

4. In combination with an electric motor of the character described, a cylinder housing, means whereby the housing may be secured to the motor and extend axially with the drive shaft of said motor, means for supporting electric lights within the housing upon the inner end thereof, a translucent member carried by the housing and positioned forward of said lights, a member of 95 transparent material carried by the housing and positioned on the forward side of said translucent member and having characters thereon, a disc loosely mounted on the shaft of said motor and positioned forward of the character member, the said disc being transparent and having slots 100 through which the characters upon the said member may be observed and also having sections of different colors, an obturator fixedly secured to the shaft forward of the rotatable disc, means between the obturator and disc for operating the latter, and a transparent closure for the 105 forward end of the housing.

5. In combination with a fan motor of the character described, a housing having one end detachably secured to the said motor to extend in axial relation to the shaft of said motor, a plurality of electric lamps carried upon the said housing, an extension for the shaft of said fan motor, a translucent disc carried by the housing, a detachable transparent member carried by the housing and positioned on the forward side of the translucent disc, a transparent disc loosely mounted on the extension shaft forward of the stationary member, said last-named disc having slots through which characters upon the stationary member may be observed and also having a colored section, an obturator fixedly 115 120 125 130 135 140 145 150 155 160 165 170 175 180

secured to the extension shaft and positioned forward of the stationary member, and a friction ring on the said shaft between the disc and obturator.

5. 6. In a device of the character described, a housing adapted to be secured to a motor housing and having a transparent closure for one end, a fan carrying shaft mounted in the housing, means for securing said shaft to a motor shaft, a plurality of lights carried upon the inner end of the housing, a translucent disc carried by the housing, a

stationary plate supported forward of the translucent disc upon which characters are placed, an obturator fixedly secured to the 15 said shaft, a transparent disc having colored sections and loosely mounted on the shaft, said disc also having slots through which the characters upon the stationary member may be observed, and a frictional 20 ring on the said shaft between the obturator and the last named transparent disc.

EMILIO RODRIGUEZ ETCHEZO
